UNITED STATES PATENT OFFICE.

FREDERICK W. MILLER, OF CHICAGO, ILLINOIS, ASSIGNOR TO FRIGID FUEL CO., OF CHICAGO, ILLINOIS.

CASKET LOWERING AND RAISING APPARATUS.

1,109,538.

Specification of Letters Patent.

Patented Sept. 1, 1914.

Application filed December 9, 1912. Serial No. 735,767.

To all whom it may concern:

Be it known that I, FREDERICK W. MILLER, a citizen of the United States, residing at Chicago, in the county of Cook and State of Illinois, have invented a certain new and useful Improvement in Casket Lowering and Raising Apparatus, of which the following is a full, clear, concise, and exact description, reference being had to the accompanying drawings, forming a part of this specification.

My invention relates to casket lowering and raising apparatus and has for its object the provision of a new and improved machine of this character.

I will describe one form of carrying out my invention more in detail by referring to the accompanying drawing illustrating said embodiment in which:

Figure 1 is a side view partially in section of my improved device; Fig. 2 is a top view thereof; Fig. 3 is a partial sectional view to illustrate the operating mechanism; Fig. 4 is an end view of the mechanism inclosing head partially in section; Fig. 5 is a sectional view to illustrate the locking means employed for adjusting purposes. Fig. 6 is a fragmentary view to more clearly reveal the collapsible features, and Fig. 7 is a sectional view on line a—a of Fig. 3.

Referring more particularly to Figs. 1 and 2 which illustrate the general nature of the device, I show a quartet of heads 1, 2, 3 and 4 between which rotatable sleeves 5 and 6 are pivotally mounted, each carrying straps 7 and 8 adapted to support the casket 9. As the weight of the casket rotates the sleeves 5 and 6, suitable means within the head 2 to be later explained regulate the speed of descent and thus permit suitably controlled operation of the device.

Referring more specifically to Fig. 3, the sleeve denoted generally at 6 consists of the outer tube 10 suitably inclosing an inner tube 11, the two tubes being slidably endwise. The tube 11 has a clutch member 12 adapted to engage a second clutch member 13 provided with pins 14 and these two clutch members are held together by the sleeve 15 having screw threaded engagement with the clutch member 13. The clutch member 13 is rigidly secured to a second inner sleeve 16 around which an outer sleeve 17 similar to the sleeve 10 is placed. A shaft 18 projects through an opening 19 of

the head 2 and this shaft 18 is rotatable having at its right hand extremity a flat member 20 adapted to engage a cooperating lug 21 having a flat face, the two being held together by means of the pin 22. The sleeve 10 carries a partition 24 having a square hole to fit the square portion of shaft 26 to rotate same. A set screw 25 passes through sleeve 10, partition 24 and enters a hole in the square shaft 18. By removing screw 25, sleeves 10 and 11 and their accompanying parts can be moved as shown in Fig. 6 so that all parts may swing around the pin 22. The plates 20 and 21 are also rectangular on their outer periphery as shown more clearly 70 in said Fig. 7 and by reason of this construction the shaft 18 rotates with the outer sleeve 10 as is apparent. The block 21 is fixedly secured to a tube 26 of rectangular cross-section, which thus rotates with this 75 element 21 and also by reason of its rectangular cross-section drives a block 27 fixedly secured to the tube 11, the block 27 also having an inner rectangular opening to conform to the rectangular outline of the tube 80 26. Now it will be apparent that the sleeves 10 and 11 are extensible longitudinally and in that event, assuming that the outer sleeve 10 is driven by the strap 7, this rotation of the sleeve 10 rotates the shaft 18 and thereby the tube 26, and through the agency of this tube 26 and the block 27 drives the inner tube 11, which thereby through the agency of the coupling drives the tube 16. Similar instrumentalities may then be interposed so that the sleeve 16 drives the sleeve 17. This power transmitting apparatus thus far described is operable it will be seen irrespective of how far the sleeves 10 and 11 are displaced longitudinally by 95 being extended to accommodate larger opening, the pin 28 preventing the tube 26 from being withdrawn entirely from the block 27.

It will of course be understood that the weight of the casket tends to drive the shaft 100 18 by reason of the instrumentalities above outlined.

My invention is designed to regulate the speed of the descent of the casket, or as will appear, to permit means of raising the same 105 should such be desired. I might say incidentally that a lug 29 is provided which prevents the collar 15 from being displaced too far. The shaft 18 is mounted in a bearing 30 and carries a bevel gear 31. This 110

bevel gear 31 meshes with a second bevel gear 32 carried upon a shaft 33. This shaft 33 transmits the movement of the bevel gear 31 to the bevel gear 34 which in turn transmits it to the bevel gear 35 to thereby drive the sleeve 5 in unison with the sleeve 10. Suitable means such as a telescoping shaft portion 36 are provided to permit of the extension of the shaft 33 whenever it is designed to increase the space between the heads 1 and 2. The head 2 is fixedly secured to a sleeve 37 and the head 1 is fixedly secured to a sleeve 38, which sleeve telescopes to permit extension and retraction. The sleeve 37 has a plurality of holes 39 into which a spring pressed pin 40 is adapted to project to lock the device in any predetermined extended position. This pin has a knurled head 41 and has a pin 42, which pin normally projects into a slot 43 when projecting into a hole 39, but which pin may ride on the upper outer surface of the cylindrical element 45 during the process of adjustment.

I will now describe the manner in which I regulate the speed of the descent and also the means that may be employed to control the ascent. When the sleeves are rotated the bevel gear 31 rotates the bevel gear 32, thereby rotating the shaft 33. This shaft 33 carries a gear wheel 46. A hub 47 is loosely mounted on the shaft 33 and this hub is integral with a worm wheel 48. A pawl 49 is pressed by means of the spring 50 into engagement with the teeth of the wheel 46 so that a contra-clockwise rotation (Fig. 4) of the shaft 33 will carry along the worm wheel 48. Should it be desired by hand to rotate the sleeve 6 so as to wind up the straps 7 and 8, then this will rotate the sleeve 5 through the agency of the gear wheels, 31, 32, 34 and 35, but the rotation in this direction will not rotate the worm wheel 48 as the pawl 49 then rides over the teeth of the gear wheel 46. During the descent of the casket, however, the forced rotation of the worm wheel 48 is communicated to the worm 51. This worm is mounted on a shaft 52, which shaft is carried at its lower extremity in any suitable manner in a bearing 53 of the head 2 and at its upper extremity in a bridge 54. The pitch of the worm and worm wheel of course is sufficiently high so that the worm wheel may impart rotation to the worm. The worm shaft 52 carries at its upper extremity a gear wheel 55 which gear wheel meshes with a suitable gear wheel 56 carried on a shaft 57, also mounted in the bridge 54. This shaft 57 carries a friction disk 58 which is slideable on the shaft 57, and may be pulled downwardly (Fig. 4) through the action of governor springs 59 which are suitably weighted by the weights 60. The lower ends of the governor springs 59 are fixedly se-

cured to the shaft 57 and the upper ends of these springs are secured to the element 58 so that in answer to the outward bending of these springs due to the centrifugal action of the weights 60, the element 58 may slide along the shaft 57. The friction disk 58 is then pulled downwardly against a cam 61, which cam may be suitably rotated and adjusted by the handle 62, a stop 63 limiting the movement of said handle 62. By reason of this cam 61 the speed of descent may be regulated. The shaft 52 protrudes upwardly out of the head 2 and may be engaged by a suitable handle 64 shown in dotted lines by means of which the apparatus may be rotated so as to elevate the casket upon the straps 7 and 8.

It will thus be seen that I have provided a very simple and efficient means of controlling the motion and providing an adjustable and collapsible machine. It will of course also be readily apparent that changes may be readily made in the structure herein shown without departing from the spirit of my invention.

Having however thus described one form which my invention may take, what I claim as new and desire to secure by Letters Patent is:

1. In a device of the character described, the combination with supporting straps, a pair of rotatable sleeves to which said straps are secured, a plurality of heads in which said sleeves terminate and on which said sleeves are rotatably mounted, means whereby said sleeves rotate synchronously, a governor to control the rotation of said sleeves when a weight is placed upon said straps, a pawl and ratchet and worm and worm wheel interposed between said sleeves and said governor, a shaft for said worm, and a bridge for supporting said worm shaft and governor shaft. 95
2. In a device of the character described, the combination with supporting straps, a pair of rotatable sleeves to which said straps are secured, a plurality of heads in which said sleeves terminate and on which said sleeves are rotatably mounted, means whereby said sleeves rotate synchronously, a governor to control the rotation of said sleeves when a weight is placed upon said straps, means for uniting one of said sleeves with said governor, said means including a square shaft and engaging power transmitting mechanism between said shaft and said sleeve, said power transmitting mechanism being slideable on said shaft and said square shaft being jointed, and means for sliding said sleeve along said shaft to permit said shaft to be folded to permit collapsing of said device. 110
3. In a device of the character described, the combination with supporting straps, a pair of rotatable sleeves to which said straps

are secured, a plurality of heads in which said sleeves terminate and on which said sleeves are rotatably mounted, means whereby said sleeves rotate synchronously, a governor to control the rotation of said sleeves when a weight is placed upon said straps, means for uniting one of said sleeves with said governor, said means including a square shaft and engaging power transmitting mechanism between said shaft and said sleeve, said power transmitting mechanism being slidable on said shaft and said square shaft being jointed, means for sliding said

sleeve along said shaft to permit said shaft to be folded to permit collapsing of said device, and a second sleeve telescoping within said last aforesaid sleeve and also having power transmitting connection with said square shaft.

In witness whereof, I hereunto subscribe 20 my name this 16th day of November, A. D., 1912.

FREDERICK W. MILLER.

Witnesses:

MAX W. ZABEL,
A. LYDA JONES.

It is hereby certified that the name of the assignee in Letters Patent No. 1,109,538, granted September 1, 1914, upon the application of Frederick W. Miller, of Chicago, Illinois, for an improvement in "Casket Lowering and Raising Apparatus," was erroneously given as "Frigid Fuel Co.," whereas it should have been given as *Frigid Fluid Co.*; and that the said Letters Patent should be read with this correction therein that the same may conform to the record of the case in the Patent Office.

Signed and sealed this 6th day of October, A. D., 1914.

[SEAL.]

R. F. WHITEHEAD,

Acting Commissioner of Patents.
